UNITED STATES PATENT OFFICE

2,583,760

GUARD RAIL FOR FOLDING BERTHS

Edward E. Woller, Kenosha, Wis., assignor to
 Simmons Company, New York, N. Y., a corporation of Delaware

Application September 24, 1948, Serial No. 51,005

7 Claims. (Cl. 5-9)

1 The main objects of this invention are, to provide an improved form of guard rail for use on berths of the type that are swingably mounted on a supporting frame for movement between an open, horizontally-disposed, sleeping position and a closed, vertically-disposed, non-usable position; to provide improved means for causing said guard rail to be automatically shifted between its erect and collapsed positions by the swinging of said bed bottom between its open and closed positions; to provide an improved guard rail of this kind comprising right-angularly-disposed sections mountable at one of the outer corners of said bed bottom; to provide a guard rail and actuating means of this kind particularly adapted for use on berths that are suspended from a supporting frame on a mechanism whereby the pivot of said mechanism to said bed bottom shifts as said bed bottom is swung between its open and closed positions; and to provide a guard rail and actuating means of this kind which is simple and economical to construct, facile to assemble, and positive in operation.

In the accompanying drawings,

Fig. 1 is a vertical sectional detail of a berth, in its open position, equipped with a preferred form of guard rail constructed in accordance with this invention;

Fig. 2 is a reduced fragmentary perspective of the guard rail end of the berth in its open position;

Fig. 3 is a similar view showing, as indicated by the arrows, the guard rail in the course of its movement from its erect position toward its collapsed position, as the berth is in the process of being shifted into its vertically-disposed position;

Fig. 4 is a view similar to Fig. 1 but showing the relative position of the guard rail when the berth is in its fully closed vertically retracted position; and

Fig. 5 is a front side elevation of the guard rail end of the berth with the parts in the positions shown in Fig. 2.

As indicated in the drawings, a berth, to which an improved guard rail constructed in accordance with this invention has been applied, comprises a supporting frame 6 whereon is swingably mounted a bed bottom 7 by means of suspension means 8, and on which bed bottom is mounted the improved guard rail 9 for shifting between its erect and collapsed positions as the bed bottom 7 is swung between its open, horizontally-disposed, sleeping position and its closed, vertically-disposed, non-usable position.

The supporting frame 6, preferably pressed 55 dotted outline in Fig. 1) supported on the bed

2 steel, includes a back 10 and a pair of end panels 11. The forward edges of the latter are formed with inwardly-disposed flanges 12 which serve to frame the bed bottom 7 in its closed position. Brackets 13 are secured to the respective end panels 11 near the back 10 to provide support for one of the links of the suspension mechanism 8, to be more fully described hereinafter, and for the support of a rubber bumper 14 which co-acts with the suspension mechanism 8 to cause horizontal disposition of the bed bottom 7.

The bed bottom 7, likewise a unitary pressed steel construction, is formed with a bottom 15, transverse lateral sides 16 and 17, and ends 18 on and within which is supported a mattress 19 (see Fig. 1). On each of the ends 18 is secured brackets 20 and 21 whereto is connected a part of the suspension mechanism 8.

The suspension mechanism 8 herein shown is of a construction more fully set forth in co-pending application Serial No. 51,006, filed Sept. 24, 1948. In the main it comprises a rocker arm 22, a pair of suspension links 23 and 24 and a spacing link 25, located at each end of the berth.

The rocker arm 22 is pivoted at 26 to a trunnion plate 27 mounted on the inner face of the frame end panel 11. The link 23 is pivoted at 28 to the rocker arm 22 and at 29 to the bracket 20. The link 24 is slightly bent at 30 whereby the two parts thereof are disposed at a slight angle to each other. The upper portion of the link 24 is pivoted at 31 to the rocker arm 22 whereas the lower portion is pivoted at 32 to the bracket 21.

The spacing link 25 is pivoted at 33 to the frame bracket 13 and at 34 to the bed bottom bracket 21.

It should be understood that the type of suspension means herein shown and described is by no means essential to the guard rail 9 presently to be described. Other forms of suspension means may be used with equal facility.

The improved guard rail 9, constructed in accordance with this invention, comprises a side member 35 and an end member 36 whose simultaneous shifting between the erect positions shown in Fig. 2 and the collapsed positions shown in Fig. 4 is effected by means of an actuating link 37.

The side member 35 is hinged to a pair of posts 38 and 39 welded or otherwise secured to the outer lateral side 16 of the bed bottom 7. The posts 38 and 39 are of such a height that the axis of the hinge connection 40 is located slightly above the plane of the top of a mattress 19 (shown in

3

bottom 7. Thus, in its collapsed position, as shown in Fig. 4, the side member 35 is permitted to fold down against the mattress 19 and whatever bedding may be on it.

The end member 36 is pivoted at 41 to the upper rail of the side member 35 and adjacent its inner end is supported by a link 42 pivoted to the bracket 20 at 29 (the pivot for the link 23) and at 43 to the lower rail of said end member 36. Thus the end member 36, by reason of the hinge connection of the side member 35 to the bed bottom 7, is in effect supported on a pair of links and is adapted to move in its own plane rearwardly downward and forwardly upward as the side member 35 shifts between its erect and collapsed positions.

The actuating link 31, by means of which the guard rail 9 is shifted between its erect and collapsed positions, is pivoted at 44 to the forward end of the adjacent bed-bottom spacing link 25 and at 45 intermediate the pivotal connections of the link 42 to the bracket 20 and the end member 36. As will be noted, the forward end of the link 37 is turned up slightly to ensure the proper shifting action of the guard rail 9 when the bed bottom 7 is swung on its suspension means 8.

The operation of this improved guard rail is as follows:

When the bed bottom 7 is swung down from its vertically - disposed, non - usable position, as shown in Fig. 4, the suspension means 8 (which, as previously pointed out, includes the spacing link 25) causes the lateral side 17 to move inwardly and upwardly as the lateral side 16 moves downwardly and outwardly. At the same time the spacing link 25 moves upwardly and outwardly about its pivot 33 until the lateral side 17 strikes the rubber bumper 14 which determines the horizontal disposition of the bed bottom 7.

The corresponding upward and outward movement of the pivot 44 on the spacing link 25 shifts the actuating link 37 outwardly along the bed-bottom end 18. This outward shifting movement of the link 37 is, in turn, transmitted to the link 42 at the pivot point 45 thereby rotating the link 42 about the pivot 29 toward an erect position more or less perpendicular to the plane of the bed bottom 7. This in turn moves the end member 36 of the guard rail 9 upwardly and outwardly in its own plane whereupon the side member 35 is rotated about the pivot points 43 into the erect position shown in Figs. 2 and 5.

When the bed bottom is shifted from its horizontally-disposed position toward its vertically-disposed position the inner lateral side 17 of the bed bottom tends to move downward and outwardly whereupon the downward and backward movement of the outer end of the link 25 causes the link 37 to swing the link 42 inwardly around its pivot 29. This inwardly swinging movement of the link 42 shifts the end member 36 of the guard rail 9 downwardly and inwardly in its own plane and, by virtue of the pivotal connection between the members 35 and 36, also causes the member 35 to swing downwardly about the pivots 40 toward its collapsed position. An intermediate position of these parts during the shifting of the bed bottom toward its vertically-disposed position is indicated in Fig. 3.

Variations and modifications in the details of structure and arrangement of the parts may be resorted to within the spirit and coverage of the appended claims.

I claim:

1. In a device of the class described, the com-

4

bination of a supporting frame, a bed bottom swingably mounted on said frame for movement between a horizontally-disposed sleeping position and a vertically-disposed non-usable position, a guard rail hingedly mounted on one of the sides of said bed bottom and swingable between a vertically-erect position when said bed bottom is in its horizontally-disposed sleeping position and a collapsed position approximating parallelism with the plane of said bed bottom when said bed bottom is in its vertically-disposed position, and link means connecting said guard rail with said frame whereby said rail is automatically shifted between the aforesaid positions with the swinging of said berth between its horizontal and vertical positions.

2. In a device of the class described, the combination of a supporting frame, a bed bottom swingably mounted on said frame for movement between a horizontally-disposed sleeping position and a vertically-disposed non-usable position, a guard rail hingedly mounted on one of the sides of said bed bottom and swingable between a vertically-erect position when said bed bottom is in its horizontally-disposed sleeping position and a collapsed position approximating parallelism with the plane of said bed bottom when said bed bottom is in its vertically-disposed position, and link means connecting said guard rail with said frame and said bed bottom whereby said rail is automatically shifted between the aforesaid positions with the swinging of said berth between its horizontal and vertical positions.

3. In a device of the class described, the combination of a supporting frame, a bed bottom, link mechanism pivoted to said frame and supporting said bed bottom on a pivot which moves horizontally inwardly and outwardly as said bed bottom is shifted between a horizontally-disposed sleeping position and a vertically-disposed non-usable position, a guard rail hingedly mounted on one of the sides of said bed bottom and swingable between a vertically-erect position when said bed bottom is in its horizontally-disposed sleeping position and a collapsed position approximating parallelism with the plane of said bed bottom when said bed bottom is in its vertically-disposed position, and link means connecting said guard rail with said frame and said bed bottom whereby said rail is automatically shifted between the aforesaid positions with the swinging of said berth between its horizontal and vertical positions.

4. In a device of the class described, the combination of a supporting frame, a bed bottom swingably mounted on said frame for movement between a horizontally-disposed sleeping position and a vertically-disposed non-usable position, a side rail hinged on the outer lateral side 60 of said bed bottom, a transverse end rail pivoted to said side rail so as to be movable in its own plane when said side rail is shifted on its pivot, and link means connecting said transverse end rail with said frame whereby with the swinging of said berth between its horizontal and vertical positions said side rail is automatically shifted between a vertically-erect position when said bed bottom is in its horizontally-disposed sleeping position and a collapsed position approximating parallelism with the plane of said bed bottom when said bed bottom is in its vertically-disposed position.

5. In a device of the class described, the combination of a supporting frame, a bed bottom swingably mounted on said frame for movement

between a horizontally-disposed sleeping position and a vertically-disposed non-useable position, a side rail hinged on posts mounted on the outer lateral side of said bed bottom so as to dispose the axis of the hinge approximately in the plane of the upper surface of a mattress resting on said bed bottom, a transverse end rail pivoted to said side rail so as to be movable in its own plane when said side rail is shifted on its pivot, and link means connecting said transverse end rail with said frame whereby with the swinging of said berth between its horizontal and vertical positions said side rail is automatically shifted between a vertically-erect position when said bed bottom is in its horizontally-disposed sleeping position and a collapsed position approximating parallelism with the plane of said bed bottom when said bed bottom is in its vertically-disposed position.

6. In a folding berth, the combination of a support, a bed bottom pivotally mounted on said support so as to be foldable to and from horizontal bed position from and to vertically disposed folded position, a guard structure in substantially parallel relation to and adjacent a side of said bed bottom which extends transversely of the axis of the pivot mounting of the bed bottom on said support, said guard structure comprising a rail and a pair of spaced links each having its opposite ends pivoted to said rail and to said bed bottom respectively, the axes of said link pivots being substantially parallel to the pivot axis of said bed-bottom mounting whereby said guard structure is shiftable sidewise relative to said bed bottom, and linkage connecting said guard structure to a portion of said support spaced from said pivot mounting and operative to effect sidewise shifting of said

guard structure as an incident to the folding movements of said bed bottom.

7. In a device of the class described, the combination of a supporting frame, a bed bottom swingably mounted on said frame for movement between a horizontally-disposed sleeping portion and a vertically-retractable non-useable position, a side rail hinged on the outer lateral side of said bed bottom, a transverse end rail pivoted at its outer end to said side rail and supported adjacent its inner end by means of a link pivoted to said bed frame so as to be movable in its own plane when said side rail is shifted on its pivot, and link means connecting said first-mentioned link with said frame whereby with the swinging of said berth between its horizontal and vertical positions said side rail is automatically shifted between a vertically-erect position when said bed bottom is in its horizontally-disposed sleeping position and a collapsed position approximating parallelism with the plane of said bed bottom when said bed bottom is in its vertically-retracted position.
